INCINERATOR DEVICE

Kenneth J. Tobin, Chicago, Ill.

Application February 6, 1933, Serial No. 655,430

18 Claims. (Cl. 126—224)

This invention relates to incinerator devices.

It is an object of this invention to provide incinerator devices for the burning or cremation of refuse comprising refuse receptacles of novel construction.

A further object is to provide incinerator devices comprising refuse receptacles which are capable of being installed more quickly and with less effort than similar receptacles of prior devices.

A further object is to provide an incinerator device comprising a refuse receptacle and means for maintaining said receptacle above a heat emitting source so as to present an unobstructed passage of heat from said source to said receptacle.

A further object is to provide an incinerator device including a refuse receptacle and means for suspending said receptacle so that accidental disengagement of said means from said receptacle is obviated.

A further object is to provide an incinerator device comprising a combustion chamber having a top portion and a refuse receptacle having an open top, the combustion chamber and the receptacle being so related that the top portion of the chamber serves as a top for the receptacle.

With the foregoing and other objects which will become clear as the description of the invention proceeds the invention comprises the novel structure and combination of parts hereinafter described and more particularly pointed out and defined in the appended claims.

In the drawings forming part of this specification:

Figure 1 is a vertical section taken through a furnace or boiler showing one embodiment of the invention, a part being broken away to more clearly illustrate the invention;

Figure 2 is a horizontal section taken on line 2—2 of Figure 1;

Figure 3 is a vertical section taken on line 3—3 of Figure 1;

Figure 4 is a fragmentary horizontal section taken on line 4—4 of Figure 1;

Figure 5 is a partial vertical section taken on line 5—5 of Figure 1;

Figure 6 is a perspective view showing a modified form of refuse receptacle; and

Figures 7 and 8 are end views of further modifications of receptacle.

The instant invention relates to improvements upon the invention disclosed in applicant's co-pending application, Serial No. 522,544, filed

March 14, 1931, now Patent No. 1,906,023, dated April 25, 1933.

Referring to Figures 1 to 5, inclusive, of the drawings which illustrate a preferred embodiment of the invention, the numeral 10 designates as a whole a furnace or boiler which preferably is of the oil-fired type and embodies an oil burner 11 of any preferred construction. The burner 11 preferably utilizes a blower so as to produce a forced draft. The furnace or boiler also includes a combustion chamber 12 above which extend the water sections 13, 14 and 15. The lower section 13 lies upon the combustion chamber 12 and, in the type of boiler illustrated, has a lower corrugated wall 13'. This section is provided with an aperture 16. Similar apertures 17 and 18 are provided in the sections 14 and 15, all of these apertures communicating with the flue 19 of the furnace or boiler. A door opening 20 leads into the combustion chamber 12 and this opening is closed by means of a door 21. A door 22 is utilized to close the space between the sections 13 and 14, as clearly shown in Figures 1 and 2 of the drawings.

In order to adapt the furnace or boiler 10 for service as an incinerator a refuse receptacle 23 is positioned within the combustion chamber 12. As clearly illustrated in Figures 1, 2 and 3 of the drawings the receptacle 23 comprises a base portion 24 and a cover portion 25. The base portion 30 embodies a bottom wall 26 which, as clearly shown in Figure 3 of the drawings, is preferably crowned and provided with side flanges 27 and 28. A rear wall 29 extends upwardly from the bottom wall 26 preferably in a smooth curve, as shown in Figure 1 of the drawings. Extending forwardly from the rear wall 29 is a pair of side flanges 30 and 31 which, adjacent their free edges, are offset as indicated at 32 and 33. The rear wall 29 is, additionally, provided with spaced lugs 34 and 35 for a purpose which will later appear.

The cover portion 25 is clearly illustrated in Figures 2 and 3 of the drawings and comprises a top wall 36 and side walls 37 and 38. It will be apparent from Figures 1 to 3, inclusive, of the drawings that the cover portion is assembled with the base portion so that the side walls 37 and 38 of the cover portion lie between the flanges 27 and 28 provided on the bottom wall 26 of the base portion. Furthermore, the rear edges of the side flanges 37 and 38 are seated within the offset portions 32 and 33 of the side flanges 30 and 31 so as to present a substantially smooth interior side wall construction for the receptacle. It is to be

observed that the construction of the receptacle described provides an open front end and, in view of the fact that the cover portion stops short of the rear wall 29, an opening 39 is provided in the top of the receptacle. This opening communicates with the flue 19 through the openings 16, 17 and 18 provided in the water sections of the boiler. The bottom wall 26 of the base portion adjacent the forward edge thereof is provided with a plurality of small openings 40. If desired a chute 41 may be pivotally connected to the front end of the receptacle in order to facilitate placing of refuse within the receptacle.

In its position within the combustion chamber 12 of the furnace or boiler the open front end of the receptacle is preferably seated within the door opening 20 customarily provided in furnaces or boilers and may be retained against accidental displacement outwardly through said opening by means of a lug 42 provided on the base portion of the receptacle. It is to be observed that the open front end of the receptacle may be closed by means of the door 21 provided for the door opening 20.

In order to maintain the receptacle in the desired position within the combustion chamber 12 and to avoid obstructing the passage of heat from the burner 11 to the receptacle the novel means of the invention is utilized. A member, preferably in the form of a bar 43, is adapted to be inserted above the lower section 13 through the door 22 and to be supported upon said section. As clearly shown in Figures 1 and 2 of the drawings the bar extends across the aperture 16 provided in the section 13 and through a ring 44 from which a chain 45 is hung. The chain extends from the ring 44 so that one of the links 46 of said chain may readily be passed between the lugs 34 and 35 provided on the rear wall of the receptacle. It will be clear that the chain extends through the aperture 39 provided in the top of the receptacle. The link 47 is positioned so as to extend across the space between the lugs 34 and 35 which rest upon said link 45 so as to suspend the receptacle in the desired position. When suspended a bolt 48 may be adjusted so as to bear against the boiler or furnace, thereby avoiding rearward movement of the receptacle and disengagement of the receptacle from the suspending chain. The bar 43, as clearly shown in Figure 1 of the drawings is preferably of such length as to extend from the front to the rear of the furnace or boiler whereby the latter is utilized to prevent movement in the direction of the length of the bar.

It will be apparent from the foregoing description that the furnace or boiler 10, in addition to its ordinary purpose for heating a building, may be utilized, as well, as an incinerator. The heat provided by the burner 11 and the receptacle positioned within the combustion chamber of the boiler or furnace constitute in this regard an incinerator. In order to effectively dispose of refuse the door 21 may be opened and where a chute is utilized this may be moved forward as indicated at 49. The refuse may then readily be placed within the receptacle 23 and the door 21 closed. Under the action of the heat supplied by the burner 11 the refuse is burned and the ash resulting from such burning has been found, as a result of actual experiment, to be decomposed into a powder. This powder, in view of the fact that the draft may enter the receptacle through the openings 40 and pass out of the

receptacle through the aperture 39, is disposed of up the flue of the furnace or boiler.

A modified form of receptacle is illustrated in Figure 6 of the drawings. This receptacle 50 comprises a bottom wall 51, side walls 52 and 53 and a rear wall 54 from which spaced projections 55 and 56 extend. An opening 57 may also be provided in the rear wall to receive the bolt 48. The bottom wall 51 is preferably crowned and the forward edge of said wall tapered downwardly as indicated at 58 so as to provide a substantially flat portion capable of being seated in the door opening 20 provided in the furnace or boiler. In its position within the combustion chamber the side walls 52 and 53 of the receptacle extend upwardly into proximate relation with troughs of the corrugated wall 13' of the lower section 13. By means of this relationship the bottom wall of said section cooperates with the side walls of the receptacle and serves as a top for closing the receptacle. It is apparent, of course, that the receptacle will be open immediately below the aperture provided in the lower section 13. The bar 43 and chain 45 may be utilized as hereinbefore described to suspend the receptacle within the combustion chamber.

Further modifications of receptacle are illustrated in Figures 7 and 8 of the drawings. The receptacle shown in Figure 7 of the drawings comprises a crowned base portion 59 and a cover portion 60. The cover portion comprises a top wall 61, a rear wall 62 and side walls 63 and 64 provided with flanges 65 and 66 upon which the base portion 59 rests. Lugs 67 and 68 may be provided on the rear wall 62 for the purpose hereinbefore set forth.

The modified receptacle shown in Figure 8 of the drawings comprises a base portion 69 having depending side flanges 70 and 71. A cover portion 72 is provided having a top wall 73, a rear wall 74 and side walls 75 and 76 which are provided with upturned flanges 77 and 78 having interlocking engagement with the flanges 70 and 71 provided on the base portion 69. Lugs 79 and 80 may be provided on the rear wall 74.

It is to be understood that in each of the receptacles shown in Figures 7 and 8 of the drawings apertures will be provided in the top walls so that suspending means may extend into the receptacles for engagement with the lugs in order to suspend said receptacles.

It is apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. An incinerator device comprising a combustion chamber, a heat source in said chamber and a refuse receptacle positioned in said chamber, said receptacle comprising a base portion adapted to be maintained in said chamber, and a separate cover portion supported by said base portion, said receptacle having an open front end.

2. An incinerator device comprising a combustion chamber, a heat source in said chamber and a refuse receptacle positioned in said chamber, said receptacle comprising a base portion adapted to be maintained in said chamber and a separate cover portion supported by said base portion, said base and cover being associated by relative horizontal sliding movement.

3. In an incinerator device having a combus-

tion chamber, in combination, a refuse receptacle positioned in said chamber, said receptacle comprising a base portion and a separate cover portion, said base portion including bottom and rear walls, said cover portion having top and downwardly extending side walls, the side walls of said covered portion constituting the side walls of said receptacle.

4. In an incinerator device having a combustion chamber, a refuse receptacle positioned in said chamber, said receptacle comprising a base portion having bottom and rear walls, flanges extending upwardly from the sides of said bottom wall, and a separate cover portion embodying top and side walls, said side walls being positioned between the side flanges of said base portion.

5. In an incinerator device having a combustion chamber, a refuse receptacle positioned in said chamber, said receptacle comprising a base portion having bottom and rear walls, flanges extending upwardly from the sides of said bottom wall, flanges extending forwardly from said rear wall and a separate cover portion embodying top and side walls, said side walls being positioned in overlapping relationship with the flanges of said bottom and rear walls.

6. In an incinerator device having a combustion chamber, a refuse receptacle positioned in said chamber, said receptacle comprising a base portion having bottom and rear walls, flanges extending upwardly from the sides of said bottom wall, flanges extending forwardly from said rear wall and a separate cover portion embodying top and side walls, said side walls being positioned in overlapping relationship with the flanges of said bottom and rear walls, and said top wall being spaced from the rear wall of said base portion to provide an opening through the top of said receptacle.

7. In an incinerator device having a combustion chamber, in combination, a refuse receptacle positioned in said chamber, said receptacle comprising a base portion and a separate cover portion, said base portion including bottom and rear walls, lugs extending from said rear wall and means attachable to said lugs for suspending said receptacle in said chamber.

8. In an incinerator device having a combustion chamber provided with a door opening and a fluid heat source, the combination with a refuse receptacle positioned in said chamber, said receptacle having an open front end seated in said door opening, of means for suspending said receptacle in said chamber, said means being provided in said incinerator and engaging said receptacle adjacent the rear end thereof to suspend said receptacle in fixed relationship to said heat source.

9. In an incinerator device having a combustion chamber provided with a door opening, a refuse receptacle positioned in said chamber, said receptacle having an open front end seated in said door opening and a top having an opening therein, a bar carried by said incinerator, a member depending from said bar and extending through said opening and means provided on said receptacle engageable with said member whereby to suspend said receptacle from said bar.

10. In an incinerator device having a combustion chamber provided with a door opening, a refuse receptacle positioned in said chamber, said receptacle having an open front end seated in said door opening and a top having an opening therein, a bar carried by said incinera-

tor, a chain hanging from said bar and extending through said receptacle opening, spaced lugs provided on said receptacle, said chain lying between and engaging said lugs to suspend said receptacle.

11. In an incinerator device having a combustion chamber, a refuse receptacle positioned in said chamber, said receptacle comprising a base portion having a bottom wall and a separate cover portion embodying top and side walls, said bottom wall and said side walls having interlocking engagement.

12. In a furnace or boiler, a combustion chamber provided with a door opening, a crown section above said combustion chamber having an opening communicating with the flue of said furnace or boiler, a refuse receptacle positioned in said chamber having an open front end seated in said door opening and a top having an opening communicating with the opening in said section, a member supported by said section, means hanging from said member and extending through the opening in said section and the opening in said receptacle and projections provided on said receptacle, said means engaging said projections to suspend said receptacle.

13. In an installed furnace or boiler, a combustion chamber provided with a door opening, a crown section above said combustion chamber having an opening communicating with the flue of said furnace or boiler, a refuse receptacle positioned in said chamber having an open front end seated in said door opening and a top having an opening communicating with the opening in said section, a member insertable into said furnace or boiler through an opening therein for support by said section extending across the opening therein, a chain depending from said member through said section and receptacle openings, spaced lugs carried by said receptacle, said chain lying between and engaging said lugs to suspend said receptacle.

14. An incinerator device comprising a combustion chamber and a refuse receptacle positioned in said chamber, said receptacle having bottom, rear and side walls and an open top and front.

15. In a furnace or boiler, in combination, a combustion chamber, a crown section covering said chamber having an opening communicating with the flue of said furnace or boiler, a refuse receptacle positioned in said combustion chamber, said receptacle having bottom, side and rear walls and an open top, said side and rear walls lying in proximate relation to said crowned section and the rear of said receptacle lying below the opening in said section.

16. In a furnace or boiler, a combustion chamber provided with a door opening, a crown section above said combustion chamber having an opening communicating with the flue of said furnace or boiler, a refuse receptacle positioned in said chamber having bottom, side and rear walls and an open top and front end, said front end being seated in said door opening and said rear and side walls lying in proximate relationship to said crowned section, the rear of said receptacle lying below the opening in said section and means for maintaining said receptacle in said chamber.

17. In an incinerator device having a combustion chamber provided with a door opening and a fluid heat source, in combination, a refuse receptacle positioned in said chamber, means for supporting the front end of said receptacle in

proximate relation to said door opening and means for adjustably suspending the rear of said receptacle with respect to said heat source, said means being provided in said incinerator and 5 engaging said receptacle adjacent the rear end thereof to suspend said receptacle in fixed relationship to said heat source.

18. In a furnace or boiler a combustion chamber provided with a door opening, a crown section above said combustion chamber having an opening communicating with the flue of said

furnace or boiler, a refuse receptacle positioned in said chamber having an open front end disposed in proximity to said door opening and a top having an opening communicating with the opening in said section, means hanging from said section and extending through the opening in said receptacle, said means being fastened to and suspending said receptacle in said combustion chamber. 5

KENNETH J. TOBIN. 10
